TENSION STAND

Alexander V. Alexeff, Cleveland, Ohio, assignor to Industrial Ovens, Incorporated, Cleveland, Ohio, a corporation of Ohio
Continuation of application Ser. No. 341,550, Jan. 31, 1964. This application Dec. 21, 1966, Ser. No. 603,686
4 Claims. (Cl. 226—195)

ABSTRACT OF THE DISCLOSURE

A tension stand having an array of cylindrical rolls which are spaced from each other and positioned for wrapping contact in a given sequence by a passing web and which are linked to each other by angular motion transmitting means for establishing substantially fixed ratios between the angular displacements of the linked rolls. At least one of the rolls is spaced from the remainder of the rolls to establish at least one long reach of web which reach substantially exceeds in length the average diameter of the rolls in the array.

This is a continuation of application Ser. No. 341,550 filed Jan. 31, 1964, now abandoned.

The present invention relates to tension stands for strips. For purposes of this application, "strips" are to be understood to include webs such as metal sheet, paper, textiles, films, and wide tape, and to also include wires, rods, narrow tapes, tubings, and filaments, such as nylon, rayon and glass fiber.

In the processing of strip material, it is usually necessary to overcome and/or resist the imposition of tension on the strip material during the treatment of the strip so that the imposition of such tension is confined to desired treating zones. For example, in the treatment of nylon fabric, it is desirable to subject the fabric to a hot-stretch treatment in which the fabric is heated and stretched following a coating or impregnating step. During the hot-stretch treatment, tension is imposed on the strip and this tension may be in the order of 20 tons or more; and during the coating or impregnating step, the tension is considerably less than 20 tons.

To accommodate the differences in tension along the entire strip, it is necessary to provide roll arrays or tension stands to overcome and/or resist such impositions of tension. The tension stands are located in the processing line at positions where it is desired to maintain tension differentials in the strip. Conventional tension stands for this purpose employ driven, geared rolls that are arranged so that the strip will have a high total angle of wrap (say 2000 degrees) through the tension stands. The rolls are conventionally nested and arranged in a compact array with short web reaches between successive rolls.

If such a conventional tension stand is employed as a hold back stand, i.e., the tension of the outgoing strip is considerably greater than that of the incoming strip, the outgoing strip will slip on the last two or three rolls when operating at line speeds. This slippage is not smooth and continuous over these rolls, but is a pulsating slippage. These pulses are violent and if the strip is under a tension of 12,500 pounds at the outgoing end of the tension stand and if the strip is traveling at 100 yards per minute, the frequency of the pulses may be between 8 and 10 pulses per second, and the pulses may reduce the strength of the processed material by approximately 10 percent.

If the tension stand is employed as an intermediate type pull roll stand, as for example where the outgoing strip is maintained under a relatively high tension and the incoming strip is maintained under an even higher tension, the rolls at the incoming end of the tension stand will

2

act as a pull stand while the rolls at the outgoing end of the stand will act as a hold back stand. This produces pulses in the strip which are similar to the violent pulses produced by the previously described stretching action, except that they occur at an intermediate location in the roll stand. In either case, however, the rolls of the tension stand and their gears are subjected to severe moment imbalances and resulting rocking loads and gear chatter or reverse pounding on the gear teeth. A solution to this problem does not reside in merely providing heavy and costly structure to resist these loads, since this undesirably tends to cause absorption of the loads by the material itself and may tend to further contribute to the weakening of the material.

It is an object of this invention to provide a roll array for a tension stand that overcomes many of these prior art problems.

It is a more particular object of this invention to provide a tension stand having a roll array that will minimize violent pulsations through the tension stand by permitting stretch and/or shrinkage to be more evenly distributed.

The invention contemplates disposing at least one of the intermediate rolls in a tension stand from its conventional, closely spaced relationship with other rolls so that at least one reach of the web substantially exceeds in length the average diameter of the rolls in the tension stand.

The features and advantages of the invention will be more apparent from the following description of a specific example thereof.

In the drawing:

FIGURE 1 is a diagrammatic illustration of a conventional tension stand;

FIGURE 2 is a diagrammatic illustration of a tension stand embodying the invention; and

FIGURE 3 is a diagrammatic illustration of another embodiment of the invention.

A conventional tension stand is illustrated in FIGURE 1, and the tension stand includes an array of rolls 10. A web W is entrained around the rolls 10 to provide a maximum angle of wrap between each roll 10 and the web. Each roll 10 is provided with angular motion transmitting means such as gears 11. The gears 11 mesh with each other according to the sequence established by the web W. One of the rolls 10 is connected to a hold back means, such as the drive shaft of a high torque capacity D.C. motor (not shown). The tension capacity of the stand is correlated to the total degrees of wrap between the web W and the rolls 10.

The conventional roll arrangement illustrated in FIGURE 1 results in relatively short reaches R between adjacent rolls 10. If the tension stand is employed as a hold back stand, with, for example, a web tension of 25,000 pounds at the outfeed end of the tension stand and a web tension of 2,000 pounds at the infeed end of the stand, then at normal line speeds slippage takes place in the form of short, violent pulses at the last few rolls of the stand.

If the tension stand illustrated in FIGURE 1 is employed as an intermediate type pull roll stand, with, for example, an infeed web tension of 25,000 pounds and an outfeed web tension of 5,000 pounds, rolls adjacent the infeed end of the tension stand will act as a pull roll stand, while the rolls adjacent the outfeed end of the tension stand will act as a hold back stand. In such an arrangement, the previously described pulsating action will occur at an intermediate location within the stand.

FIGURE 2 illustrates a tension stand embodying the invention. The tension stand includes an array of rolls 12. A web W is entrained through the rolls 12 in a predetermined sequence to establish a maximum angle of wrap

between each roll 12 and the web. Each roll 12 is provided with angular motion transmitting means such as gears 13. The gears 13 and a gear 14 establish a gear train that drives the rolls in the sequence established by the web W. One of the rolls 12 is connected to a hold back means, such as the drive shaft of a high torque capacity D.C. motor (not shown). The tension capacity of the stand is correlated to the total degrees of wrap between the web W and the rolls 12.

A roll 15, which would conventionally be associated with the gear 14, is spaced from its immediately adjacent upstream and downstream rolls to provide relatively long reaches L, as compared to the relatively short reaches R that are established between the rolls 12. The relatively long reaches L provide an additional unwrapped length of strip material in the tension stand. At even the highest line speeds, the provision of this additional unwrapped length greatly minimizes the previously described pulsing in the web. The roll 15 may be driven by a linkage from the gear 14 if it is necessary to utilize the wrapped surface of the roll 15 as an additional tensioning means. If the degree of web wrap over the rolls 12 is adequate for the imposition of a predetermined tension on the web W, the roll 15 may be an idler roll.

The particular roll that establishes the relatively long reaches L is immaterial as long as these reaches are established at an intermediate stage in the tension stand. For purposes of this application, an intermediate stage is to be understood as a zone between the point or line of contact that the web makes with the first roll at the infeed end of the tension stand and the line or point of contact that the web makes with the roll at the outfeed end of the tension stand.

It should also be appreciated that minimization or elimination of pulsation may be enhanced by increasing the lengths and the number of the relatively long reaches L that are established in the tension stand. Thus, it may be desirable in some instances to position more than one roll a substantial distance from its immediately adjacent upstream and downstream rolls. In any case, however, a reach L should be greater than the average diameter of the rolls in the tension stand in order to effectively minimize pulsations in the web.

In FIGURE 3, a tension stand is illustrated that includes an array of rolls 16 that are all positioned remote from their adjacent upstream and downstream rolls to provide relatively long reaches L of a web W which is trained through the rolls. The rolls 16 are driven in the direction established by the web W by suitable angular motion transmitting means, such as the gears 17, which are associated with the rolls 16. This driving relationship between the rolls 16 is further established by intermediate gears 18. One of the rolls 16 or one of the intermediate gears 18 are connected to a hold back means, such as the drive shaft of a high torque capacity D.C. motor (not shown). The tension capacity of the stand is correlated to the total degrees of wrap between the web W and the rolls 16.

The invention is not restricted to the slavish imitation of each and every one of the details described above, which have been set forth merely by way of example with the intent of most clearly setting forth the teachings of the invention. Obviously, devices may be provided which change, eliminate, or add certain specific details without departing from the invention.

What is claimed is:

1. A web tension stand for maintaining a substantial tension differential between the portions of web entering the stand and the portions of web leaving the stand comprising an array of rolls including a plurality of web-tension-absorbing rolls positioned so that a web may be sequentially wrapped therearound with contact between such web and said web-tension-absorbing rolls along a substantial peripheral portion thereof, rigid torque transmitting means interconnecting said rolls including rigid elements operable in both tension and compression to maintain a constant fixed ratio between the angular displacements of said rolls with substantially no lost motion or free travel even when torque impulses occur, said rolls being operable to maintain a first tension in web at one end of said array and a second tension substantially different than said first tension in such web at the other end of said array, the tension in such web in the reaches between said web-tension-absorbing rolls progressively changing from said first tension to said second tension, and said array including at least one roll establishing at an intermediate stage in the sequence of such web through said array at least one long reach of web which substantially exceeds the length of the average diameter of said web-tension-absorbing rolls whereby pulsating slippage between such web and said rolls is substantially reduced.

2. A web tension stand as set forth in claim 1 wherein said rigid torque means includes meshing gears interconnecting said web-tension-absorbing rolls with at least one gear mounted on each roll.

3. A web tension stand as set forth in claim 2 wherein the gears mounted on each roll directly mesh with at least one gear on another roll.

4. A web tension stand as set forth in claim 2 wherein idler gear means interconnect at least two of said gears mounted on said rolls.
